UNITED STATES PATENT OFFICE.

KONRAD RIDOCAR RITTER, OF LEIPZIG-SCHÖNEFELD, GERMANY.

MACHINE FOR WINDING ARMATURES FOR DYNAMO-ELECTRIC MACHINES.

1,190,801.

Specification of Letters Patent.

Patented July 11, 1916.

Application filed August 1, 1914. Serial No. 854,528.

To all whom it may concern:

Be it known that I, KONRAD RIDOCAR RITTER, engineer, a subject of the Emperor of Austria-Hungary, residing at 4 Vostitz-Wallitzstrasse, Leipzig-Schönefeld, Germany, have invented new and useful Improvements in Machines for Winding Armatures for Dynamo-Electric Machines, of which the following is a specification.

10 This invention relates to machines for winding armatures for dynamo-electric machines of the type in which holding means for the armature provided with guides for the wire to be wound thereon and a wire delivering device are arranged so as to rotate relatively to each other about an axis at right angles or substantially at right angles to the armature shaft.

15 The invention consists in the special construction of the holding device for the armature and the wire delivery device, and in other detail improvements in the construction of the machine as hereinafter described.

20 The invention will be described with reference to the accompanying drawings, in which one form of construction is illustrated.

25 Figure 1 is a front view of the machine. Fig. 2 is a diagrammatic plan view showing the relative positions of the armature and the holding cheeks. Fig. 3 is a front view of a holding cheek with a wire guiding device. Fig. 4 is a plan of same. Fig. 5 is a section through the holding cheek on line 30 5-5 of Fig. 3.

35 On two supports *a*, *a'* are mounted the bearing pedestals *b*, *b'* in which are journaled the shafts *c*, *c'* of two disks *d*, *d'*. In each of these disks are fitted two holding 40 cheeks *e*, *e'* (Fig. 2) provided with extension pieces *f* (Figs. 3 and 4). Between these cheeks the armature *g* is gripped in such a manner that its axis *h* is at right angles to the shafts *c*, *c'*. The shaft *c'* is arranged so 45 that it can, by means of a screw *i*, a hand-wheel *k* and a spring suitably arranged, be moved a greater or lesser distance toward the armature *g* in order to grip the latter tightly between the cheeks *e*, *e'*.

50 Upon the disks *d*, *d'* are secured, in any suitable manner, holders *l*, *l'* which serve for the support of horn-like shaped guide devices *m* or of wire holders *n*. When the armature is wound so that the windings 55 pass on only one side of the shaft, the guide horns *m* are secured in the holders *l* on one

side, said guide horns *m* serving to hold the wire from engagement with the armature shaft, as more fully described below. The wire holder *n* may then be secured in the 60 holder *l'* as also more fully described hereinafter.

On the holding cheeks *e*, *e'* are adjustably secured the wire guides *o*, *o'* which serve to guide the wire directly into the armature groove to be wound. The wire is wound from a supply spool (not shown in the drawings) behind the supports *a*, *a'* and passes through the opening *p* over the spring rollers or tension rollers *q*, *q'* and 70 then to one of the guide horns *m* and past the wire guides *o*, *o'* to the wire holder *n* to which it is secured by its end. The shafts *c*, *c'* are then, by means of the pulley *r* or in any other suitable manner, caused to rotate continuously, so that the wire *s* is 75 wound in the armature groove determined by the position of the wire guides *o*, *o'*. It is to be observed that wire guides *o*, *o'* are also provided on the opposite side of the armature to those shown, the bent out ends of which in the arrangement of the parts shown in Fig. 1 would extend downward, but these are omitted from the drawing so as not to unnecessarily complicate it. The 80 horns *m*, during winding, guide the wire as it passes from the supply spool away from the armature shaft *h*.

When a winding is finished the wire is again led to the wire holder *n* and cut off, 90 then, by means of the foot lever *t*, through the medium of the shaft *u*, the link *v* and the bell-crank lever *w*, the cheek *e'* may be withdrawn somewhat in order that the armature *g* may be turned around to present the next groove for winding, when the foot lever is released and cheek *e'* again moves forward to grip the armature. To permit of being rotated in this way, the armature is carried upon a conical pointed foot-step 95 *x*, which enters the end of the armature shaft and is mounted upon an arm *y* carried by the support *z*. The latter is secured to one of the cheeks *e* in any suitable manner.

100 If many coils with few windings are to be wound on the armature, the number of wires to be introduced simultaneously, not exceeding three, the wire, in order to simplify the operation, is not cut after the completion of the first three windings, but only led over the hook *n* and then further wound.

This is repeated until all the coils to be wound in the groove are completed. Then the combined wires are cut directly in front of the hook *n*, so that for each of the separate coils there are two corresponding wire ends, of which one remains bent over the hook *n* and represents the beginning of the coil, while the other, standing out, forms the end of the coil. This lightens the work of connecting up the corresponding wire ends. Before cutting the wires, the coils are secured, by wooden wedges or the like, in the two grooves of the armature containing them, so that they cannot become loose when the wires are cut.

The guide horns *m* are mounted by means of pivots 2 on the heads 3 of spindles 4 and by means of right and left handed screws 5 in correspondingly double threaded nuts 6 are pivotally connected to the heads 3 so that by rotation of the nuts 6 they may be inclined more or less with regard to the armature shaft *h*. Their position can also be regulated radially by means of the nuts 7 upon the spindles 4. These nuts bear against blocks 8 slidably mounted on the spindles and carried by brackets 10 adjustably secured by means of the set screws 11 in the holders 7. A spring 9 is provided on the end of the spindle 4 to maintain the nut 7 always in engagement with the block 8.

The wire guides *o*, *o'* are constructed as shown in Figs. 3, 4 and 5 in such a manner as to be adjustable upon the cheeks *e*, *e'*. In the arrangement shown the cheek *e* has the form of a prism. The guide *o* is mounted on a lever 12 pivoted at 13' to a slide 13. The lever 12 and guide *o* may be adjusted relatively to said slide by means of a nut and screw 14; upon the latter is mounted a spring 15 the tendency of which is to push the lever 12 away from the cheek.

In the slide 13 is provided the spindle 16 of a toothed wheel 17, which can be rotated by means of a head 18. The pinion 17 engages in rack 19 secured upon the cheek *e* so that on rotation of the pinion 17 the slide 13 together with the guide *o* is moved in the guideway or groove 20 (see Fig. 5) formed in the cheek. The slide 13 may, by means of the screw 21, be rigidly secured in the position desired. In this way it is possible to quickly and exactly adjust the wire guide *o* both in the direction toward and away from the shaft of the armature and around or across the armature. To be able, should it be necessary also to adjust the guide *o* into a somewhat different direction or inclination, it is not immovably secured upon the lever 12, but is pivotally mounted upon a screw or pin 22, and is held in position by means of a screw 24 passing through a slot in the guide carrier 23.

In order that in cases in which for any

reason it may be desired for a while to move back the guide from the armature, it may be possible on its return to bring it immediately into the original position without lengthy adjustments, there is provided on the side wall of the slideway or groove 20 an adjustable stop consisting of two blocks 25 and 26 connected by a set screw 27. When the guide *o* has been adjusted, the stop is moved against the face of the slide 13 and secured there by means of the screw 27. Should the guide *o* subsequently be moved away for any reason, it is only necessary on returning it to push it up against the stop to bring it to the proper position. Should it be necessary to wind the armature so that the wire passes on both sides of the armature shaft it will be necessary to replace the wire holder *n* by a guide horn similar to the horn *m* and extending over the other side of the armature shaft. It is of course obvious that the machine may also be constructed so that the cheeks with the armature remain stationary while the wire supply spool is arranged to rotate about the apparatus.

Having thus described the nature of my said invention and the best means I know of carrying the same into practical effect, I claim:

1. In a machine for winding armatures for dynamo-electric machines, of the type in which a holder for the armature and a wire supply spool are rotated relatively to each other about an axis at right angles or substantially at right angles to the armature shaft, a wire guide carried by the armature holder capable of adjustment away from or toward the armature and around or across it, substantially as hereinbefore described.

2. In a machine for winding armatures for dynamo-electric machines, of the type in which a holder for the armature and a wire supply spool are rotated relatively to each other about an axis at right angles or substantially at right angles to the armature shaft, holding cheeks to support the armature and slides mounted thereon carrying wire directing guides capable of adjustment away from or toward the armature and around or across it, substantially as hereinbefore described.

3. In a machine for winding armatures for dynamo-electric machines, of the type in which a holder for the armature and a wire supply spool are rotated relatively to each other about an axis at right angles or substantially at right angles to the armature shaft, holding cheeks to support the armature and slides mounted thereon carrying wire directing guides and stops to determine the movement of said slides, substantially as hereinbefore described.

4. In a machine for winding armatures for dynamo-electric machines, of the type

in which a holder for the armature and a wire supply spool are rotated relatively to each other about an axis at right angles or substantially at right angles to the armature shaft, a pivoted and adjustable guiding horn carried by the apparatus to direct the wire out of engagement with the armature shaft, substantially as hereinbefore described.

10 5. In a machine for winding armatures for dynamo-electric machines, of the type in which a holder for the armature and a wire supply spool are rotated relatively to each other about an axis at right angles or substantially at right angles to the armature shaft, a guide horn to direct the wire out of engagement with the armature shaft, and means for adjusting said guide horn in a direction radial to the axis of the machine, substantially as hereinbefore described.

15 6. In a machine for winding armatures for dynamo-electric machines, of the type in which a holder for the armature and a wire supply spool are rotated relatively to each other about an axis at right angles or

substantially at right angles to the armature shaft, a guide horn to direct the wire out of engagement with the armature shaft and a wire holder adapted to hold the ends of the several coils, substantially as herein- 30 before described.

7. In a machine for winding armatures for dynamo-electric machines, of the type in which a holder for the armature and a wire supply spool are rotated relatively to 35 each other about an axis at right angles or substantially at right angles to the armature shaft, a guide horn to direct the wire out of engagement with the armature shaft and a wire holder adapted to hold the ends of the 40 several coils arranged on the opposite side of the machine to the guide horn, substantially as hereinbefore described.

In testimony whereof I have signed my name to this specification in the presence 45 of two subscribing witnesses.

KONRAD RIDOCAR RITTER.
